UNITED STATES PATENT OFFICE.

FRANK F. WEAR, OF SAN FRANCISCO, CALIFORNIA.

DISPLAY-BIN.

No. 922,738.

Specification of Letters Patent.

Patented May 25, 1909.

Application filed January 29, 1909. Serial No. 475,063.

To all whom it may concern:

Be it known that I, FRANK F. WEAR, a citizen of the United States, residing at San Francisco, in the county of San Francisco 5 and State of California, have invented new and useful Improvements in Display-Bins, of which the following is a specification.

The object of the present invention is to provide an improved display bin for containing tea, coffee, or salable material of any kind in which it is important that the material should be displayed in an attractive manner, and easily inspected by an intending purchaser, while at the same time preserved from admixture with foreign particles and undue exposure to dust. The bin is especially designed for the reception and display of tea or coffee, as it permits of these substances being readily inspected without 10 opening the bin, and at the same time preserves them in a perfectly clean and sanitary condition.

In the accompanying drawings, Figure 1 is a vertical transverse section of a receptacle 25 containing display bins constructed in accordance with my invention and especially adapted for displaying coffee; Fig. 2 is a horizontal section of the same on the line 2—2 of Fig. 3, showing one of the bins partly 30 withdrawn; Fig. 3 is a rear view of the same upon a reduced scale.

Referring to the drawing, 1 indicates a base mounted upon legs 2. Supported upon the rear side of said base are vertical frame 35 pieces 3, preferably of wood, and, secured to said frame pieces, are the rear vertical edges of ends 4 and a partition 5. Secured to the front edges of said ends 4 and partitions 5 is a front side 6, and supported upon said front 40 side, the ends 4, the partition 5, and the rear frame pieces 3, is a top 7. Said ends, partition, front side and top are all made of glass, secured to each other by cement, thus forming a closed receptacle which is open to inspection at top, front, and sides. The space 45 within said receptacle is divided by the partition 5 into two chambers, but it is to be understood that, in general, there are two or more partitions, correspondingly dividing 50 the receptacle into three or more chambers. In each chamber there is detachably supported a bin 8, open at the top. The bottom 9, sides 10, and front 11 of said bin are made of suitable metal, and its sides are, at 55 their rear edges, bent into flanges 12, which

are secured to vertical cleats 13. The rear side 14 of the bin, to about one-half of its height, is also formed of metal, reinforced by a wooden backing 15. To the top of the part of the back so formed there is hinged, as 60 shown at 16 a lower door 17, the upper edge of which closes against a cleat 18 extending horizontally across the rear of the bin at about the level of its top, and to the upper edge of said horizontal cleat 18 is also hinged, 65 as shown at 19, an upper door 20, which closes against a cleat 21 extending across between the frame pieces 3, close to the top of the receptacle. When the pin is inserted in position, it slides between the vertical edges 70 of the vertical frame pieces 3, and is then secured by means of screws 22 screwed to said frame pieces through the vertical cleats 13.

The bin is of such dimensions that, when in position, as shown at the right hand side of 75 Fig. 2, there is left a narrow space 23 in the front and at each side between the bin and the corresponding compartment of the receptacle, which space is filled with coffee, or other salable product of the same character 80 as that within the bin itself. Extending obliquely downward and forward from the cleat 18, and its edges being secured to the sides of the bin is a partition 25, the object of which is to support the coffee or other material in the bin forward or away from the lower opening, so that, while the upper surface of the coffee in the front part of the bin may be at a considerable height, as shown in dotted lines at 26, that in the rear part of the 90 bin slopes downward rearwardly from the rear and front edge of said partition, as shown at 27. This latter surface remains substantially the same whatever be the level of the surface of the coffee in the front part 95 of the bin until the coffee has been exhausted to a level below the rear front edge of said partition. Consequently, although the bin may be full, or nearly full, of coffee, yet the surface of the coffee to which the scoop is to 100 be applied for removing the same remains substantially uniform until the greater part of the coffee has been removed from the bin.

The front and rear inner surfaces of the bin extend downward with rounded surfaces to 105 the bottom of the bin to avoid angular corners, the object being to prevent coffee or other material lodging in said corners for so long a time as to become stale before being sold.

I claim:—

A display bin having a top side, a front side, end sides, and a partition, all of glass, and forming a receptacle having compartments open to inspection at the top, front and ends, a bin removably supported in each compartment, open at the top, said cabinet having means for spacing the bin from the sides of the cabinet to form display chambers, whereby said spaces may be filled with a comparatively small quantity of the commodity to be displayed, the front and rear inner walls of the bin being continued with rounded surfaces to the bottom thereof to

15 avoid angular bottom corners, said bin having in its rear side an opening, a door for closing said opening, and a partition extending from said rear side immediately above said opening and obliquely downward therefrom to a point above the bottom of the compartment, substantially as described.

20 In testimony whereof I have hereunto set my hand in the presence of two subscribing witnesses.

FRANK F. WEAR.
